Primary Examiner — Sanjeev Paul(74) Attorney, Agent, or Firm — Sheridan Ross P.C.(57) CLAIM

The ornamental design for a seat cushion, as shown and described.

DESCRIPTION

FIG. 1 is a front perspective view of the seat cushion showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view.

The broken lines show portions of the seat cushion which form no part of the claimed design.
